UNITED STATES PATENT OFFICE

2,052,618

FASTENING INSERTING MACHINE

George Goddu, deceased, late of Winchester, Mass., by Isabelle W. Goddu, executrix, Winchester, Mass., assignor to United Shoe Machinery Corporation, Paterson, N. J., a corporation of New Jersey

Application April 23, 1934, Serial No. 721,852

16 Claims.

(Cl. 1—20)

This invention relates to fastening inserting machines and is illustrated herein as embodied in a machine of the type disclosed in United States Letters Patent No. 1,016,930, granted February 5 13, 1912, on an application filed in the name of William H. Borden.

Machines of the type disclosed in this patent are extensively used to secure together shoe parts, either temporarily or permanently. Under many 10 conditions it is desirable to present successive portions of the work manually to the operation of the fastening inserting instrumentalities to insert fastenings at such portions of the work as may be necessary. Under some conditions, for example 15 when securing repair soles to shoes, fastenings are inserted successively along substantially the entire edge of the work and in such cases the work is ordinarily presented or fed manually to the fastening inserting instrumentalities but, to insure that the fastenings will be properly spaced 20 from each other to fasten the parts securely together without inserting an excessive number of fastenings, the operator must exercise considerable care in feeding the work. This manual feeding or positioning of the work for each successive 25 fastening inserting operation requires considerable skill and care on the part of the operator, and considerable time is expended in properly positioning the work. It is evident, therefore, 30 that such manual feeding or positioning of the work consumes considerable time with the result that production of work on machines of this type is substantially reduced.

An object of the present invention is to provide 35 work feeding mechanism particularly adapted for use in machines of the type referred to. To this end one feature of the invention comprises means for feeding a work piece past a fastening inserting means, a distortable member connected 40 between the feeding means and a means for distorting the member while the work is under clamping pressure, the distortable member being constructed and arranged to operate the feeding means when clamping pressure on the work is released. 45 As illustrated, the feeding mechanism comprises a feeding member yieldably held in engagement with the work piece, a lever pivotally mounted on the machine and connected at one end to the feeding member, and a resiliently ex- 50 tendsible link connected at one end to the other end of said lever and adjustably connected at its other end to a cam operated bell crank lever, the link being constructed and arranged to be placed under tension when a staple is being formed and, 55 when clamping pressure on the work is released

after a staple has been driven, to cause the feeding member to feed the work past the nozzle of the machine.

Other features and objects of the invention will be apparent from a consideration of the following description and claims in connection with the accompanying drawing, in which

Fig. 1 is a view in front elevation of a staple inserting machine embodying the present invention; and

Fig. 2 is a view in side elevation of the work feeding mechanism.

The present invention is illustrated as embodied in a machine of the type disclosed in the above-mentioned United States Letters Patent No. 1,016,930. The wire controlling and feeding mechanism of the machine disclosed in the patent above referred to has been modified as disclosed in United States Letters Patent No. 1,432,770, granted October 24, 1922, on an application filed 15 in the name Fred L. MacKenzie, and the machine has been provided with a work support of the type disclosed in United States Letters Patent No. 1,852,152, granted April 5, 1932, on an application filed in the name of Louis G. Dingel- 20 day. Reference may be had to the above-mentioned patents for a complete disclosure of such parts of the machine as it is unnecessary to describe and illustrate herein.

As is usual in machines of this type, the head 2 30 of the machine is mounted upon a column 4. A cam shaft 6 is journaled in suitable bearings in the head 2 of the machine and carries cams for operating the fastening forming and inserting instrumentalities of the machine. A lifter cam 35 8 is mounted on the forward end of the cam shaft 6, the cam being provided with a portion 10 which is arranged to engage a projection on a driver bar 12 carrying a driver 15. When the cam portion 10 passes from beneath the projection on the 40 driver bar 12, the driver bar is forced downwardly under the influence of a spring (not shown) to insert fastenings into a work piece.

The illustrated machine is provided with mechanism for feeding staple wire to a fastening 45 forming mechanism. The wire is fed by means of a feeding mechanism of usual type illustrated at 14 into the path of movement of an outside former 16 carried by a slide 18. The outside former slide is arranged for reciprocation in ways 50 formed in the front of the machine and partially surrounds the driver 15. Secured to the upper end of the outside former slide 18 is one arm 20 of a bell crank lever 21. The bell crank lever 21 is made fast to a rock shaft 22 by means of a 55

clamping screw 24. There is also secured to the rock shaft 22 an arm (not shown) which carries at one end a cam roll arranged to fit into a groove of a cam carried by the shaft 6 to raise 5 and lower the outside former slide 18. The machine is also provided with an inside former 26 about which staples are formed by the action of the outside former 16. The parts of the machine thus far described are substantially the same as 10 those disclosed in the Letters Patent above referred to.

A lever arm 28 formed as a part of the bell crank lever 21 is provided with an arcuate slot 30 into which fits a stud 32 which may be locked in 15 adjusted position by a nut 34. Pivoted to the front of the machine by means of a pin 36 is a lever 38 which carries at its upper end a threaded stud 40 which is locked in place on the arm 38 by means of a nut 42. The lever 38 is connected to 20 the lever arm 28 by a heavy spring 44, normally un tensioned (Fig. 1), one end of which encircles the stud 40 and the other end of which surrounds a collar 46 mounted on the adjustable clamping member 32. The spring 44, when un tensioned, is 25 stiff enough to act as a link, in either direction of stress. A feeding member 48 is pivoted to the lower end of the lever 38 by a bolt 53 provided with a nut 55, the upper end of the feeding member 48 being forked, as shown in Fig. 2, to 30 receive the lower end of the lever 38. The work engaging end of the feeding member 48 is bifurcated as shown in Fig. 2, to permit the end of the feeding member to pass beyond a nozzle 50 through which staples are driven into the work. 35 It is to be noted that the bifurcated work-engaging portions of the feeding member 48 are provided with pricker points which dig into the work. The feeding member 48 is provided with a laterally extending portion 52 which carries a pin 54 to which is connected a spring 56 secured at its upper end to a pin 58 mounted in a laterally extending portion of the lever 38. The spring 56 is under tension and thus tends at all times to force the lower end of the feed member 48 into 40 engagement with the surface of the work.

The spring connection between the lever arm 28 and the lever 38 above referred to is arranged to operate the feeding member 48 after a staple has been inserted in the work and clamping pressure on the work has been released. When the machine is put into operation the lever arm 20 is moved in a counterclockwise direction, thus forcing the outside former slide 18 downwardly to form a staple about the inside former. During 55 this counterclockwise movement of the lever arm 20, the lever 28 is also rotated in a counterclockwise direction and since the notched or forked end of the feeding member 48 is in spurred engagement with the surface of the work piece 60 which is held against the nozzle 50 by pressure placed upon the work, for example a shoe 62, by a work support 60, the feed member 48 is not permitted to move and, consequently, the spring 44 is stretched or placed under tension. When 65 clamping pressure of the work support 60 is removed after a staple has been inserted in the work, the distorted or tensioned spring 44 will rotate the lever 38 in a clockwise direction about its fulcrum 36, thus moving that point of the shoe 70 62 with which the feeding member 48 is in engagement past the nozzle 50 to position the shoe for the reception of another staple. After the shoe has been fed, the outside former slide 16 is moved upwardly to permit another length of 75 staple wire to be fed forwardly into the path of

the forming mechanism. When the former slide is moved upwardly the lever arm 20 is moved in a clockwise direction and carries with it the lever 38, since the then untensioned spring 44 acts as a link, thus moving the feeding member 48 into its retracted position, as shown in Fig. 1.

The lever arm 28, as previously stated, is provided with an arcuate slot 30, in which the member 32 is adjustably mounted. When it is desired to change the extent of feeding movement 10 of the feeding member 48 the nut 34 may be loosened and the member 32 moved in the slot 30 to the desired position. The slot 30 is non-circular with respect to the pivot 40 as center and by adjusting the member 32, as above mentioned, 15 along the slot 30 the spring 44 will cause the work to be fed variable distances past the nozzle 50 of the machine. By virtue of this construction, adjustment of the stud 32 in the slot 30 will change the initial position of the forked end of the feeding member 48. If the stud 32 is moved toward the rockshaft 22, the lever 38 will be rotated in a clockwise direction under the pull of the spring 44, now acting as a simple link, thus moving the forked end of the feeding member 48 nearer to 20 the nozzle 50. When the arm 28 is thrown counterclockwise a correspondingly small elongation of the spring 44 will result, since the arc of movement of the stud 32 is small, and when the work is released and the spring snaps back to its 25 unstressed length a small feeding movement will result. If, on the other hand, the stud 32 is moved toward the lower end of the slot 30, the lever 38 will be pushed by the spring 44, acting as a link, in the opposite or counterclockwise direction, thus moving the forked end of the feeding member 48 farther away from the nozzle 50. In this case, when the arm 28 moves counter-clockwise, the spring 44 is stretched a good deal, 30 and its collapse into unstressed condition is attended by a large feeding movement of the spurred member 48. In all cases the feeding movement is proportional to the stretch of the spring 44. It is to be noted that lowering of the horn 60 allows the work to be fed past the nozzle 45 50 of the machine by the sudden release of tension of the spring 44.

Although the parts of the machine have been described in detail it may be well at this point briefly to describe the operation of the machine. 50 After the shoe 62 has been placed upon the work support and the horn 60 moved upwardly into clamping position the clutch of the machine is tripped, thus causing the main shaft 6 of the machine to rotate. The wire feeding mechanism 14 will then be operated to feed wire 71 to the right and into the path of movement of the outside former 16. A length of wire is severed from the wire 71 as the outside former is moved downwardly to form the wire about the inside former 60. 55 During this movement of the outside former 16, the spring 44 is being stretched but movement of the lever 38 is prevented by engagement of the feeding member 48 with the bottom of the shoe 62 which is firmly clamped between the nozzle 50 and the work support 60. After the staple has been formed the inside former 26 is moved rearwardly. The projection 10 on the cam 8 then moves from beneath the projection on the driver bar 12, thus permitting the driver bar to be 70 thrust downwardly to drive the staple through the throat or nozzle 50 and into the work. After the staple has been driven the horn 60 is depressed thereby relieving pressure on the work, which will permit the tension of the spring 44 to be released, 75

thus moving the feeding member 48 toward the left to feed the work past the nozzle 50 of the machine. The parts of the machine are then returned to their initial position and the machine is in readiness to perform another cycle of operations.

Having described the invention, what is claimed as new and desired to be secured by Letters Patent of the United States is:

- 10 1. In a fastening inserting machine, means for inserting fastenings in a work piece, work clamping means, a spurred means for feeding the work past the fastening inserting means, a distortable member connected to said feeding means, and means for distorting said member while the work is under clamping pressure, a portion of said member being held against the distorting stress by the engagement of the spurred means with the work while clamped, said member being constructed and arranged to operate the feeding means when clamping pressure on said work is released.
- 15 2. In a fastening inserting machine, fastening inserting means, means for feeding the work past the fastening inserting means, work clamping means, a resilient link connected at one end to said feeding means, and means connected to the other end of said link for tensioning it while the work is under clamping pressure, said resilient link being constructed and arranged to operate the feeding means upon release of clamping pressure on the work.
- 20 3. In a fastening inserting machine, means for forming fastenings from a length of fastening material, means for inserting fastenings in a work piece, means for feeding the work piece past said fastening inserting means, and means connected to the feeding means arranged to be distorted prior to the fastening inserting operation to operate said feeding means after a fastening is driven.
- 25 4. In a fastening inserting machine, means movable to form fastenings from a length of fastening material, means for inserting said fastenings into a work piece, and a member arranged to engage said work piece and to feed said work piece past the fastening inserting means after a fastening has been inserted in the work and before the forming means is returned to its initial position.
- 30 5. In a fastening inserting machine, means movable to form fastenings from a length of fastening material, means for inserting said fastenings into a work piece, means arranged to engage the work piece to feed the work piece past the fastening inserting means, and means connected to said forming means and to said feeding means for operating said feeding means after a fastening has been inserted into the work piece and before the forming means is returned to its initial position.
- 35 6. In a fastening inserting machine, means movable from an initial position to form fastenings from a length of fastening material, means for inserting fastenings into a work piece, and a member arranged to engage said work piece and to feed said work piece past the fastening inserting means after a fastening has been inserted and before the forming means is returned to its initial position.
- 40 7. In a fastening inserting machine, means for forming fastenings from a length of fastening material, means for feeding the fastening material to said forming means, a member constructed and arranged to operate said forming means to form a fastening, means for inserting a fastening into a work piece, a member arranged to engage said work piece and to feed said work piece past the fastening inserting means, and connections between said feeding means and the forming means constructed and arranged to move the feeding means, and the work piece in engagement therewith, past the fastening inserting means after a fastening has been inserted in the work.
- 45 8. In a fastening inserting machine, means for inserting fastenings into a work piece, means arranged to engage said work piece and to feed said work piece past the fastening inserting means, and a spring connected to the feeding means constructed and arranged to be placed under tension prior to the fastening inserting operation to operate the feeding means after a fastening has been inserted in the work piece.
- 50 9. In a fastening inserting machine, means for inserting staples into a work piece, means for feeding the work piece past the fastening inserting means, and a spring for operating the feeding means constructed and arranged to be placed under tension prior to the fastening inserting operation and to be released to feed the work past the inserting means after fastenings have been inserted in the work.
- 55 10. In a fastening inserting machine, means for applying clamping pressure to a work piece, means for inserting fastenings in said work piece, means for feeding the work past said inserting means, and a member connected to said work feeding means, said member being arranged to be distorted prior to the fastening inserting operation and arranged to return to normal condition when clamping pressure on the work is released after a fastening has been inserted in the work, thereby operating said feeding means.
- 60 11. In a fastening inserting machine, means for inserting staples in the work piece, means for operating the staple inserting means, a nozzle through which said staples are driven, a support for the work constructed and arranged to apply clamping pressure to the work between successive feeding movements of the work, a member arranged to engage the work, and a spring connected to said member constructed and arranged to be placed under tension prior to the insertion of a staple and, when pressure on the work is released, to move said member to feed the work past the inserting means.
- 65 12. In a fastening inserting machine, means for applying clamping pressure to a work piece between successive feeding movements of the work, a driver for inserting staples into the work, means for feeding the work past said driver, a resilient link connected at one end to said feeding means, and operating means connected to the other end of the link constructed and arranged to place said link under tension when clamping pressure is applied to the work, thereby causing the link to operate the feeding means when clamping pressure on the work is released.
- 70 13. In a fastening inserting machine, an inside former, an outside former, means for operating said outside former to form a staple about said inside former, a driver for inserting staples into a work piece, a nozzle through which the staples are driven, a work support arranged to clamp the work against said nozzle between successive feeding movements of the work, a feeding member arranged to engage the work, and a spring connecting said feeding member to said outside former operating means, said spring being con-

structed and arranged to be distorted when a staple is being formed and, when returning to normal condition after a staple has been inserted and clamping pressure on the work released, to 5 operate said feeding means to feed the work past said nozzle.

14. In a fastening inserting machine, a driver for inserting the staples into a work piece, a nozzle through which the staples are driven by the 10 driver, a work support arranged to clamp the work against the nozzle between successive feeding movements of the work, a feeding member yieldingly held in engagement with the work, a lever pivotally mounted on the machine and secured at one end to said feeding member, a spring 15 connected to the other end of said lever, and means connected to said spring constructed and arranged to tension the spring before a staple is driven, said spring operating, when clamping pressure on the work is released after a staple 20 has been driven, to move said feeding member to feed the work past said nozzle.

15. In a fastening inserting machine, a driver for inserting staples into a work piece, a nozzle 25 through which said staples are driven by said driver, a work support arranged to clamp the work against said nozzle between successive feeding movements of the work, a work feeding member spring-urged into engagement with the work, 30 an operating lever pivotally mounted on the machine and pivotally connected at one end to said feeding member, a spring connected to the other

end of said lever, and means connected to said spring constructed and arranged to tension said spring, said spring operating, when clamping pressure on the work is released after the staple has been driven, to move said feeding member through said lever to feed the work past the nozzle. 5

16. In a fastening inserting machine, an inside former, an outside former, a cam-operated bell crank lever constructed and arranged to operate the outside former to form staples from a length of staple wire, a driver for inserting staples into a work piece, a nozzle through which the staples are driven by the driver, a work support constructed and arranged to clamp the work against the nozzle between successive feeding movements of the work, a feeding member yieldingly held in engagement with the work, a lever pivotally mounted on the machine and secured at one end to said feeding member, and a spring connected 20 to the other end of said lever and adjustably connected to said cam-operated bell crank lever whereby feeding movement of said feeding member may be varied, said spring being constructed and arranged to be placed under tension when a staple is being formed and, when clamping pressure on the work is released after a staple has been driven, to operate said feeding member to feed the work past the nozzle. 25
